UNITED STATES PATENT OFFICE

163,915

SUGAR DISPENSER

Harry L. Wall, East St. Louis, Ill.

Application January 15, 1951, Serial No. 13,804

Term of patent 14 years

(Cl. D58—26)

To all whom it may concern:

Be it known that I, Harry L. Wall, a citizen of the United States, residing at East St. Louis, in the county of Saint Clair, and State of Illinois, have invented a new, original, and ornamental Design for a Sugar Dispenser, of which the following is a specification, reference being had to the accompanying drawing, forming part thereof.

Figure 1 is a perspective view of a sugar dispenser showing my new design;

Figure 2 is a perspective view thereof as it appears when observed from the side opposite the side shown in Figure 1;

Figure 3 is a cross-sectional view of the sugar dispenser top taken substantially on the plane of the line 3—3 in Figure 1, looking in the direction of the arrows.

The essential features of the design are shown in full lines in Figures 1 and 2.

I claim:

The ornamental design for a sugar dispenser as shown and described.

HARRY L. WALL.
